CLAIM

The ornamental design for a “multiple chamber drinking cup” as shown and described.

DESCRIPTION

FIG. 1 is a front elevational view of a first embodiment of a multiple chamber drinking cup showing our new design, with the rear elevational view being a mirror image; FIGS. 2 and 3 are right and left side elevational views of the embodiment of FIG. 1;

FIG. 4 is a top plan view of the embodiment of FIG. 1; FIG. 5 is a bottom plan view of the embodiment of FIG. 1; FIG. 6 is a side elevational view of a second embodiment of a multiple chamber drinking cup showing our new design, with the opposite side elevational view, and the front and rear elevational views, being identical;

FIG. 7 is a top plan view of the embodiment of FIG. 6; and, FIG. 8 is a bottom plan view of the embodiment of FIG. 6. The broken lines are for illustrative purposes only and form no part of the claimed design.
